UNITED STATES PATENT OFFICE

ERNEST DAVIS, OF SYRACUSE, NEW YORK, ASSIGNOR TO THE PROSPERITY COMPANY
INC., OF SYRACUSE, NEW YORK, A CORPORATION OF NEW YORK

EQUALIZING MECHANISM FOR PRESSING MACHINES

Application filed May 12, 1928. Serial No. 277,110.

This invention relates to pressing machines as garment and laundry pressing machines in which the cooperating pressing elements are multiple or consist of a plurality of members; 5 the members of one element having relative movement under the pressure of the other element. The invention has for its object a particularly simple and efficient fluid pressure operated means for equalizing the pressure 10 between the relatively movable members of one of the cooperating pressing elements.

The invention consists in the novel features and in the combinations and constructions hereinafter set forth and claimed.

15 In describing this invention, reference is had to the accompanying drawing in which like characters designate corresponding parts in all the views.

Figure 1 is a front elevation partly in section of the coating pressing elements of a 20 pressing machine embodying my invention.

Figure 2 is an end elevation of parts seen in Figure 1.

Figure 3 is a side elevation of a complete 25 pressing machine embodying my invention.

Figure 4 is a view similar to Figure 1 of a modified form of the invention.

1 and 2 designate respectively the cooperating 30 pressing elements as a whole, these being respectively a head and a buck, the head being movable toward and from the buck. Each member 1 and 2 is here shown as having a plurality of pressing members, the members of the head being designated 3, 4 and 5 and 35 the members of the buck paired therewith being designated 6, 7 and 8. The members of one of these elements are movable relatively to each other under the pressure of the members of the other element and in the illustrated 40 embodiment of my invention, the members 6, 7 and 8 of the buck are relatively movable.

The machine here shown is a shirt pressing machine and adapted to press the neck yoke, neck band and cuffs of a shirt in one operation. The members 3, 6 press the neck yoke and neck band of shirts having unattached collars and the neck yoke and collars of shirts having attached collars. The pairs of members 4, 7 and 5, 8 press the cuffs.

50 In the form of my invention shown in Fig-

ure 1, the equalizing means are provided between all three members 6, 7 and 8 and in the form shown in Figure 4, the equalizing means is provided only between the outside or cuff 55 pressing members 9 and 10.

In the illustrated embodiment of my invention, the fluid pressure operated means comprises a pressure chamber, one for each of the relatively movable members 6, 7, 8 or 9 and 10, a movable pressure actuated part in each 60 of the chambers and motion transmitting means between each of said parts and the respective relatively movable member associated therewith.

The pressure chambers are, in the illustrated embodiment of my invention, shown as cylinders 11, 12 and 13 suitably mounted in the body 14 of the lower pressing element and these are connected by an equalizing conduit 15. The movable part in each cylinder is a 70 piston 16, 17 or 18.

The motion transmitting means between the pistons and the members 6, 7 and 8 comprises levers 19, 20, and 21, each lever being pivoted between its ends at 22 to the body 14 75 of the buck 2, and one arm thereof being pivotally connected at 23 to the stem 24, 25 or 26 of the corresponding piston 16, 17 or 18 and the other arm of the lever thrusting against a pedestal 27, 28 or 29 which supports the 80 corresponding member 6, 7 or 8. The stem 27, 28, or 29 is slidably mounted in a suitable guide opening in the body 14 of the buck 2.

A hydraulic fluid as oil may be used in the system including the cylinders and the 85 equalizing conduit, or compressed air may be used and the equalizing conduit may be connected to a suitable source of supply through a feed pipe 30 and the pressure in the cylinders may be reduced or increased, as desired, 90 to reduce or increase the pressure between the pairs of members 3, 6; 4, 7 and 5, 8.

The head 1 is supported in any suitable manner as by a yoke lever 31 pivoted between its ends at 32 to a standard 33 rising from 95 the frame 34 of the machine, and the body 14 of the buck 2 is mounted on the frame or a table 35 forming a part thereof.

The head 1 or the lever 31 may be actuated 100 in any suitable manner either by man or

motor power and is here shown as actuated by a piston movable in the cylinder 36 and having its rod 37 connected to one arm 38 of an angle lever pivoted to the frame, the other arm 39 of the angle lever being pivoted at 40 to the lower end of the link 41 forming a toggle therewith. The upper end of the link 41 is pivoted to the rear arm of the yoke lever 31. The piston is single acting and when the pressure in the cylinder 36 is released, the press is opened by a counterweight 42 and springs 43 and 44.

The flow of motive fluid to and from the cylinder 36 is controlled in any suitable manner as by a push button 45 and lever 46. The means for actuating the head and for controlling the operation thereof forms no part of this invention and is not necessary for an understanding thereof. It is sufficient to bear in mind that the press is opened and closed in any suitable manner.

In Figure 4, the intermediate member 60 of the buck is rigidly mounted on the buck, but the two outside members which press the cuffs are movably mounted in the same manner as the members 7 and 8 of the machine shown in Figure 1 and there are pressure chambers 12', 13' with pistons 17' and 18' movable therein which are connected through lever 20' and 21' to the members 9 and 10. These chambers 12' and 13' are connected by an equalizing conduit 15'.

In operation, when the head closes if the pressure is not equal between the members of the buck, the pressure is equalized through the cylinders, the equalizing conduit and the levers 19, 20 and 21 and the full pressure delivered may be varied by varying the amount of pressure in the cylinders so that the cylinders may act to some extent as actuators for the members 6, 7 and 8.

This pressing machine is of the type shown in my Patent No. 1,682,488 issued August 28, 1928, in which a mechanical means is shown for equalizing the pressure between the movable members of the buck.

What I claim is:

1. In a pressing machine, the combination of cooperating pressing elements, one of which is movable toward and from the other and each including a plurality of members paired with the members of the other element, the members of one element being movable relatively to each other under the pressing action of the members of the other element, means for equalizing the pressure between the relatively movable members of one of said elements including pressure chambers, one for each of the relatively movable members of said element, an equalizing conduit connecting said chambers, a pressure operated part movable in each chamber, and motion transmitting means including levers between each of said parts and its associated relatively movable member, and a feed pipe

for a fluid under pressure connected to the equalizing conduit.

2. In a pressing machine, the combination of cooperating pressing elements, one of which is movable toward and from the other and each including a plurality of members paired with the members of the other element, the members of one element being movable relatively to each other under the pressing action of the members of the other element, and means for equalizing the pressure between the relatively movable members of one of said elements including pressure chambers, one for each of the relatively movable members of said element, an equalizing conduit connecting said chambers, pressure operated parts in the respective chambers, and motion transmitting means between the pressure operated parts and their respective relatively movable members including a lever interposed between each of said parts and its associated relatively movable member.

In testimony whereof, I have hereunto signed my name at Syracuse, in the county of Onondaga, and in the State of New York, this 2nd day of May, 1928.

ERNEST DAVIS.
